CLAIM

The ornamental design for an industrial control component face plate, as shown and described.

DESCRIPTION

FIG. 1 is a front, top perspective view of an industrial control component face plate;

FIG. 2 is a rear, top perspective view thereof;

FIG. 3 is a top plan view thereof;

FIG. 4 is a right side view thereof; and,

FIG. 5 is a left side view thereof.

The broken lines shown represent unclaimed subject matter and form no part of the claimed design.

1 Claim, 5 Drawing Sheets
